MARKING TAG

Sidney E. Van Tuyl, Riverside, Ill., assignor to
American Tag Company, Chicago, Ill., a corpora-
tion of Illinois

Application May 16, 1941, Serial No. 393,712

7 Claims. (Cl. 40—25)

This invention relates to marking tags, and particularly tags which after application to a garment or article to be marked, cannot be removed without destruction or evident mutilation of the tag.

In the sale of wearing apparel and household equipment such as rugs and window drapes it is desirable to mark each article with a tag bearing the usual indicia necessary for the operation of a commercial establishment, such as the dealer's cost in code, the stock number, the selling price, the size, and such other data as are customarily kept for proper maintenance of merchandising records.

For the protection of the records it is necessary that this data be kept with the tag until the article is ultimately disposed of and retained by the purchaser, particularly as the data is especially necessary where the article is returned for credit after it has been delivered to a prospective purchaser. It is also necessary to protect against the return of an article for credit after it has been used.

For these purposes a satisfactory marking tag must be so made that it can be readily applied to a garment and cannot be removed therefrom without destruction or evident mutilation of the tag, in order that substitution of another tag can be readily detected and the removal and replacement of the tag after the article has been used will be readily apparent.

One of the objects of this invention is to provide a tag of this character which can be readily applied to wearing apparel or other articles and which can then be locked against removal without destruction or mutilation of the tag.

Another object of this invention is to provide a marking tag of this character in which the pin or fastening means by which the tag is attached to the article to be marked may be locked within a securing device to prevent the manipulation of the fastening pin to effect its removal from the garment.

Another object of the invention is to provide a marking tag of the character described which can be easily and cheaply made and which can be instantly and readily used in the conventional manner.

The above and other objects and advantages of the invention will be apparent from the following description when read in connection with the accompanying drawing, in which:

Figure 1 is an illustrative representation of a dress with a marking tag of this invention applied to one sleeve thereof;

Fig. 2 is a representation in perspective of one form of marking tag of this invention opened and ready for application to an article;

Fig. 3 is a representation in perspective of the marking tag shown in Fig. 2 applied to an article, of which a fragment is shown with one leg of the pin or fastening means placed in a slot in the rivet by which the marking tag is secured and locked together;

Fig. 4 is a view of the marking tag shown in Figs. 2 and 3 after the tag has been closed and the rivet swaged to lock the marking tag upon the article;

Fig. 5 is a fragmentary sectional view of the marking tag shown in Figs. 2, 3 and 4, taken on the line 5—5 of Fig. 3;

Fig. 6 is a fragmentary sectional view of the rivet in the marking tag shown in Figs. 2, 3, 4 and 5, taken on the line 6—6 in Fig. 5.

Fig. 7 is a fragmentary sectional view of the closed tag shown in Fig. 4 taken on the line 7—7 in Fig. 4, and showing the application of the swaging tools to the rivet upon the completion of the swaging operation;

Fig. 8 is a view in perspective of a modified form of marking tag of this invention in which a separate retainer strip is employed;

Fig. 9 is a view in section of the tag shown in Fig. 8 applied to the article to be marked and with the rivet swaged into closed position.

Fig. 10 shows a modified form of marking tag of this invention ready to be applied to the article to be marked; and

Fig. 11 is a view in section of the tag shown in Fig. 10 applied to the article to be marked and with the rivet swaged into closed position.

Referring to the drawing, the dress, which is a representation of an article to be marked, is indicated by the reference numeral 12. Applied to the sleeve 13 thereof is the marking tag 14.

As shown in Fig. 2, this marking tag comprises a tag body 15 bent over so that a portion 16 thereof overlaps the tag body 15 and forms a retainer strip overlying the rivet or eyelet 17 which passes through the tag body 15 and is designed to pass through the aperture 18 in the retainer strip 16.

The rivet 17 is of the form of that shown in the patent to Swett, No. 1,831,207, although obviously slight modifications in the form of this rivet may readily be made without departing from the substance of this invention. The rivet or eyelet 17, as best shown in Figs. 5 and 6, is formed from a tubular body having a flange or base 20 at one end thereof to engage one side

of the tag body 15 through which the tubular body portion 19 projects. The tubular body portion is slotted by the slot 21 and the material struck out from the body by the slotting operation, clinched or turned down to form the tangs 22 by which the rivet or eyelet 17 may be held in the tag body 15 prior to its use. In the event that it is not desired to have the rivet or eyelet 17 permanently attached to the tag body prior to use, the slot may be cut into the tubular body 19 of the rivet without providing the tangs 22.

Passing through the tag body 15 at the upper end thereof is the conventional pin or fastening means 23 by which the marking tag can be attached to the article to be marked merely by passing one of the legs 24 through the article to be marked (which is indicated by the numeral 25 as shown in Fig. 3). The pin 23 is shown formed with two legs 24, although obviously it may be made with a single leg and secured to the tag body 15 in any conventional manner. It is important, however, that the pin 23 be so located on the tag with respect to the rivet 17 that when the tag is closed, as shown in Fig. 4, the pin cannot be removed from the material through which it is passed, and for this purpose it is also necessary that there be sufficient space between the rivet 17 and the point at which the pin 23 is attached to the tag body 15 to permit the pin to pass through the article to be marked 25 without having any portion of the article 25 interfere with or overlie the rivet 17.

The rivet or eyelet 17 is so formed that when the tag has been completed and attached to an article the tubular body 19 of the rivet may be swaged or clinched shut by the swaging dies 26 and 27 which are normally mounted on the jaws of a pair of pincers so they may be readily manipulated. When the rivet 17 is swaged with these dies, the flanges 28 will be formed on the open end of the rivet to secure it to the retainer strip 16 in the same manner as the flange 20 retains the other end of the tubular rivet upon the tag body 15.

A modified form of the marking tag of this invention, shown in Figs. 8 and 9, is composed of the tag body 35, the separate retainer strip 36 which is apertured by the aperture 38. The rivet 17 and the pin 23 employed in this structure may be of the same form and the positioning thereof similar to that of the parts previously described in connection with the structure shown in Figs. 2 to 7, inclusive. The dotted lines on Fig. 8 indicate the position of the retainer strip 36 when applied to the marking tag in the manner contemplated by this invention.

In Figs. 10 and 11 is shown a further modification in which the tag body 45 is part of a long strip of tag material folded to form the retainer strip 46, apertured at 48; with an intermediate portion 49, apertured at 50; and a tab portion 51, which may form a severable coupon which is ordinarily detached from the tag when the garment is sold or passed through one of the stages of the merchandising procedure. The tag of Fig. 10 is shown in Fig. 11 in fragmentary section applied to an article 25 which is being marked thereby.

Method of operation

The marking tag of this invention is used in the following manner: Assuming a structure shown in Figs. 2 to 7, inclusive, the complete marking tag shown in Fig. 2 is attached to the article 25 by passing one or both of the leg mem-

bers 24 of the pin 23 through the article to be marked, as shown in Fig. 3. Thereupon one of the leg members 24 is dropped in the slot in the rivet or eyelet 17 and the retaining strip 16 folded over so as to pass the aperture 18 over the rivet 17. Thereupon the rivet 17 is swaged shut to form the flanges 28 upon the open end of the rivet by the swaging tools 26 and 27 as shown in Fig. 7.

10 Swaging tools in Fig. 7 are shown of such a type that they will not only swage the flanges 28 upon the rivet 17, but will also deform the leg member 24 of the pin 23 at the intermediate portion 29 of the leg 24, thus not only locking the pin within the rivet 17, but deforming the pin so as to prevent its subsequent use and to readily disclose that the pin has been subjected to the swaging tools. If it is not desired to deform the leg portion of the pin, it is only necessary to 20 modify the forms of swaging tools employed.

Once the rivet 17 has been swaged shut, as shown in Fig. 7, it is impossible to remove the retaining strip 16 from the tag body 15 without obvious mutilation of the retainer strip or the tag body, and the pin 23 cannot be withdrawn from the rivet 17 without serious and manifest deformation of the pin.

The modified form of the marking tag of this invention shown in Figs. 8 and 9 is applied in 30 the same manner as that previously described except that the retainer strip 36 is a separate strip and not a folded portion of the tag body. The pin 23 is passed through the article 25 in the same manner as that previously described 35 and one leg 24 of the pin dropped in the slot of the rivet 17. The retainer strip is thereupon applied and the rivet swaged shut.

The modified form of marking tag of this invention shown in Figs. 10 and 11 is handled in 40 practically the same manner as that of the form 45 first described except that the multiple folds of the tag comprising the retainer strip 46 and the intermediate portion 49 must be passed over the rivet 17 before the rivet is swaged shut.

Although the invention has been disclosed in 50 connection with the specific details of a preferred embodiment thereof, it is to be understood that such details are not intended to be limitative of the invention except insofar as set forth in the accompanying claims.

What I claim is:

1. A marking tag comprising a tag, a retainer strip, a rivet passing through the tag and the retainer strip, a slot in the rivet, a pin secured 55 to the tag, and a leg on the pin passing through the article to be marked and projecting through the slot in the rivet.

2. A marking tag comprising a tag, a retainer strip, a rivet passing through the tag and the retainer strip, a slot in the rivet, and a fastening pin secured to the tag and having a leg thereof passing through an article to be marked and disposed between the tag and the retainer strip and secured within the slot of the rivet when the rivet is swaged.

65 3. A marking tag comprising a tag, a pin secured thereto, a rivet passing through the tag, a slot in the rivet, a leg on the pin designed to pass through an article to be marked and to project into the slot in the rivet, and a retainer strip connected to the tag to overlie a portion of the tag and the pin and having an opening therein to receive the rivet so that it may be secured to the tag by swaging of the rivet.

70 4. A marking tag comprising a tag, a fasten-

ing pin secured to the tag and passing through an article to be marked, a rivet passing through the tag, a slot in the rivet receiving a portion of the fastening pin, and a retainer strip secured to the tag by the rivet so as to embrace that portion of the fastening pin passing through the rivet between the tag and the retainer strip.

5. A marking tag comprising a tag, a fold in the tag whereby a plurality of portions thereof are brought into overlapping relation to each other, a rivet passing through the overlapping portions of the tag to lock them together, a slot in the rivet, a fastening member secured to the tag, and a leg on the fastening member passing through an article to be marked and lying between the overlapping portions of the tag, the fastening member and the rivet being so positioned on the tag that the leg passes through the article to be marked and then projects through the slot in the rivet to be retained therein when the rivet is swaged to lock the overlapping portions of the tag together.

6. A marking tag comprising a sheet having

foldably connected tag and retainer portions, a pin carried by one of said portions and adapted to pass through an article to which the tag is to be secured, a rivet carried by one of said portions and having a slot in its end to receive a part of the pin which has passed through the article, the other portion having an opening to receive the rivet whereby the two portions can be secured together with the pin between them.

10 7. A marking tag comprising a sheet of paper or the like, a pin secured to the sheet adjacent one edge and having an elongated body adapted to pass through an article to be marked, a retainer sheet to overlie the first sheet and the body 15 of the pin, a rivet carried by one of the sheets and formed with a slotted end to receive the body of the pin, and the other sheet being formed with an opening to receive the rivet so that the rivet can simultaneously secure the sheets together and grip the body of the pin between them.
